[57] CLAIM

The ornamental design for a clothes hanger holder, as shown and described.

DESCRIPTION

FIG. 3 is a rear elevational view thereof;

FIG. 4 is a right side elevational view, with the clothes hanger holder in open condition;

FIG. 5 is a bottom plan view thereof; and

FIG. 6 a front elevational view thereof.
